UNITED STATES PATENT OFFICE.

ALBERT V. T. DAY, OF NEW ROCHELLE, NEW YORK, ASSIGNOR, BY MESNE ASSIGNMENTS, TO HALL SWITCH & SIGNAL COMPANY, OF NEW YORK, N. Y., A CORPORATION OF MAINE.

RAILWAY SIGNALING SYSTEM.

1,213,161.

Specification of Letters Patent. Patented Jan. 23, 1917.

Application filed August 22, 1908. Serial No. 449,756.

To all whom it may concern:

Be it known that I, ALBERT V. T. DAY, a citizen of the United States, residing at New Rochelle, in the county of Westchester and State of New York, have invented a certain new and useful Improvement in Railway Signaling Systems, of which the following is a specification, reference being had therein to the accompanying drawings, 10 forming part thereof.

My invention relates to automatic electric traffic-controlling systems for railroads, and relates more particularly to block signal systems adapted for operation in connection with electric railroads.

In certain block signal systems the operation of the signal-controlling apparatus involves the electrification of track circuits formed by the rails, or portions thereof. 20 Where the track circuits are constantly energized throughout the system, as has been proposed in such systems, a relatively great waste in energy results, and generating apparatus of relatively great capacity 25 must be provided.

One object of the present invention is to avoid such waste of energy in signal systems or other traffic-controlling systems, by the use of automatic apparatus by which 30 the track circuits are so controlled that they are normally deenergized, and are energized only in those blocks or portions of the line which are within the zone or section occupied by, or adjacent to, a train or trains on 35 the line, so that the track circuits are energized only where and when their operation is involved in the traffic control.

In certain systems employing normally energized track circuits and operating on 40 the normal safety principle, the use of automatic apparatus of the kind above referred to, without other changes in the systems, results in converting them from the normal safety principle to the normal danger principle, and a second object of my invention 45 is to thus convert such systems into normal danger systems by the application of such automatic apparatus.

In railway signaling systems employing 50 track circuits it is common to so connect the sources of signaling current with the track rails that these sources are short-

circuited by the trains or cars as they pass over the line.

Another object of the present invention 55 is to avoid such short-circuiting, since it is wasteful of energy.

In carrying out my invention, I use apparatus operating automatically, but controlled by or from the trains themselves, 60 for controlling the track circuits, this apparatus operating as the train moves through the line to connect the track circuits for a certain distance in advance of the train with the sources of current for energizing them, 65 and to disconnect the track circuits as soon as they have completed their traffic-controlling functions, and preferably the track circuit of the block or section occupied by the train is disconnected immediately upon the entrance of the train to the block or section to avoid short-circuiting by 70 the train.

Other objects and features of the invention will be set forth in connection with 75 the description of the illustrated embodiment thereof.

I will now describe the embodiment of my invention illustrated in the accompanying drawings and will thereafter point out 80 my invention in claims.

Figures 1 and 2 represent contiguous portions of a block signal system embodying my invention, Fig. 1 being the eastern or right-hand portion, and Fig. 2 the western, 85 or left-hand continuation of the same.

The drawings illustrate the west-bound track and its signal apparatus of a double-track railroad, and include three complete blocks. The east-bound track and its signal apparatus are omitted, being similar in general construction and principle of operation to those shown. The four illustrated signal stations are designated, respectively, by the letters B, C, D and E, 95 while the eastern or right-hand end of the initial block or section is indicated at A.

The apparatus at all the signal stations except the first is the same, and similar reference numbers are used for corresponding 100 parts, followed, where necessary, by letters to indicate the stations at which the designated parts are located.

The invention is shown as used in connec-

tion with a signal system disclosed in an application of Clarence W. Coleman, Serial Number 421,314, filed March 16, 1908. The Coleman system is adapted for use in connection with electric railroads in which the track rails are utilized as a part of the circuit for transmission of the traction current and in the drawings of the present application the track rails 1 and the third rail or trolley wire 2 are shown connected with an alternating current generator 3 which supplies the traction current. The track rails are divided into blocks or sections by heavy cross-bonds 4 of negligible impedance, so as to serve both as efficient conductors for the traction current and also as conductors for the inductive track circuits peculiar to the Coleman system. Within the rails, at the ends of the blocks, are located the inductive track coils 5 and 6 by which the signal control is effected.

The automatic track-circuit controlling apparatus is arranged in sets located, except in the initial section, at the middles of the several track circuits. Five such sets are illustrated, designated from east to west as *a*, *b*, *c*, *d* and *e*.

The inductive track coils 5 and 6, when in operation, act to energize track relays 7 and 8 which control the line circuit at respective ends of a block. These relays are of the polarized alternating-current type, in which a field magnet is alternately polarized in opposite directions by alternating current in the field magnet winding. The field magnets of the illustrated relays are energized through feed wires 9 and 11 connected with the secondary terminals of a transformer 12 at each station. The primary windings of the transformers are energized by a transmission line comprising a line wire 14 and the third rail 2, and the transmission line is fed by a generator 15 which generates current of a frequency substantially different from that of the traction generator 3, so that the apparatus responsive to the signal-operating current will not, under any circumstances, respond to the traction current.

Each relay has a pivoted armature 16 carrying a contact finger 17 or 18 and provided with a coil connected in circuit with one of the track coils 5, 6. The currents in the field coils and the armature coils of the relays, being derived from the same source, have the same frequency and their phase relation is such that the armatures, when properly energized, tend to rotate in the direction to keep the contact fingers in engagement with coöperating fixed contacts connected in circuit with the line wires which control the signals.

Each track circuit is energized by a transformer, of which the secondary winding 21 is connected with the two rails at the mid-

dle of the circuit. The current proceeds from one terminal of the secondary winding, through the rail connected thereto in opposite directions to the ends of the track circuit, thence through the cross-bonds 4, to the opposite rail, and back to the transformer.

The primary winding 22 of each track transformer is energized from the transmission line already referred to, comprising the wire 14 and the third rail 2.

The operation of the track-circuit transformers is controlled by the automatic track-circuit apparatus, which acts to energize and deenergize the track circuits according to the position of the train.

The track-circuit controlling apparatus differs somewhat in arrangement according to the length of the blocks. In the illustrated system, blocks BC and CD are comparatively short blocks, and a single divided track circuit extends throughout each block. In these blocks, therefore, a single complete set of track-circuit apparatus is used for each block. Block DE, however, is represented as a block of such length that it is undesirable or impracticable to control it by a single track circuit. This block is therefore divided at the middle by a cross-bond 65 similar to the cross-bonds 4, and two independent track circuits are used in the two halves of the block, each of these track circuits being energized by a separate transformer. In order that the branches of these circuits at the middle of the block may control the line circuit of the block, inductive track coils 76 and 77 are located at the ends of these branches and connected with the armature coils of relays 78 and 79 similar to the relays 7 and 8. The field magnets of these relays are energized by a transformer 80 fed by the transmission line, and the contact fingers and fixed contacts are arranged in the line circuit by connection with the line wire 61.

Since both track circuits in block DE control the same signals, they must be both energized and deenergized at the same time, and as a complete set of automatic track-circuit controlling apparatus is used at *e*, the apparatus at *d* is arranged merely as a repeater to coördinate the control of the two track circuits.

The track circuit-controlling apparatus at *b*, *c* and *e* comprises, in each set, two relays, which are arranged to operate both independently and in conjunction with each other. At *b* and *c* and *e* one relay 23 directly controls the primary circuit of the track transformer by means of the contact finger 24, which is connected by a wire 25 with the transmission line wire 14. The contact finger coöperates with a fixed contact connected with the primary winding 22 of the transformer. Normally this circuit is

open and the track circuit deenergized, but when the magnet of the relay 23 is energized, the contact finger 24 moves to the right and closes the circuit, thereby energizing the 5 track circuit controlled thereby.

The relay 23 of each set is energized through a line circuit extending to the next set in the rear. This line circuit comprises a line wire 26. The current for operating 10 the relays may be obtained from the traction-current line. At *b* and *c* and *e* the magnet of the relay 23 is connected by a wire 27 with one of the track rails, and in this case the current is derived from the traction 15 generator 3.

The line circuit of each relay 23 passes also through the magnet of the relay 28 next in the rear, and is controlled, in part, by the contact fingers 29 and 31 actuated by this 20 relay 28, and also, in part, by the contact finger 32 of the relay 23 next in the rear.

Each contact finger 32 is actuated by an armature so constructed or controlled that it is less responsive to the magnet of the relay 25 23 than is the armature controlling the contact finger 24. Hence, a stronger current is required to actuate the contact finger 32, and this arrangement is indicated diagrammatically by showing the contact finger 32 as 30 weighted. When a current of minor strength energizes the relay 23, the contact finger 24 alone closes its circuit, while a current of full strength causes both contact fingers 24 and 32 to close their circuits.

35 The means through which the relays 23 and 28 are controlled primarily by the train comprise contact members 34 arranged to be engaged by moving contacts carried by the train. These members may be arranged 40 close alongside the third rail, so as to be engaged by the ordinary contact shoes of the train. In any case, the object is to so arrange them that they are temporarily connected electrically with the main portion of 45 the third rail as the train passes. This may be done by arranging for the contact shoe or trolley wheel to engage both the contact member and the third rail simultaneously, but this is unnecessary when two or more 50 contact shoes or trolley wheels are carried by a train and connected together, for in such a case one shoe or wheel may engage the contact member 34 while another shoe or wheel engages the third rail or the trolley 55 wire.

The apparatus is arranged to energize the track circuits in the two blocks next in advance of that occupied by a train, so that both the home and the distant signal ahead 60 may be suitably controlled while the block occupied by the train is deenergized, thus avoiding the waste of energy resulting from a closed and short-circuited track circuit.

65 The operation of the track circuit controlling apparatus, as affected by a train moving

westwardly through the system, will now be described. Suppose a train at A starts toward block BC. In order that the signals at B may be cleared to admit the train, it is necessary to energize the track circuits in 70 the blocks BC and CD. The track circuit controlling apparatus will be set into operation for this purpose when the train engages the contact member 34 at the end of the initial section, but in order to afford plenty 75 of time for the clearing of the signals, it is desirable to start the automatic action before the train reaches B, and for this purpose an auxiliary contact member 70 is provided some distance in the rear of B. This 80

contact member is connected with the magnet of a neutral relay 71 and thence, through a wire 72, with the wire 35 by which the contact member 34 is connected with the apparatus at *b*. When the train engages the 85 contact member 70, traction current is sent through the relay 71 and through the wires 72 and 35 to *b* and the automatic apparatus is thereby operated to energize the track circuits. At the same time, the relay 71 acts 90 upon its contact finger 73 and thereby closes a stick circuit which passes from the third rail through a wire 74 to the contact finger and its cooperating fixed contact, and thence through the relay magnet. This stick circuit remains closed after the train has passed over the contact member 70 and continues the transmission of current to *b* until the train engages the contact member 34^b. When 95 this occurs, the relay 71 is short-circuited by 100 the direct connection of the contact member 34 with the third rail, and the relay 71 thereupon releases its contact finger and opens its stick circuit. The action of the auxiliary contact member 70 and the relay 105 71 is therefore substantially the same as if the contact member 34 were elongated to extend to the position occupied by the contact member 70.

The current from the contact member 70 110 energizes the relay 23^b and causes it to actuate its contact finger 24 to close the circuit through the primary winding 22 of the track transformer, and thus the track circuit is energized in the block BC. The relay 23^b 115 also actuates its contact finger 32, and thereby closes a circuit through the magnet of the relay 28^b. This circuit passes from the third rail 2 through a wire 36, a resistance coil 37, and the contact finger 32, and thence through 120 a wire 39, to the magnet of the relay 28. From this magnet the current flows, through the line wire 26 and an interposed resistance coil 33, to the magnet of the relay 23^c. From this magnet the circuit is continued to the track rails, and the magnet is energized and it at once attracts the armature controlling the contact finger 24, and thus the track circuit is energized in the block CD, and thus 125 two blocks in advance of the train are ener- 130

gized. The operation does not proceed further, however, for the current which energizes the relay 23^c is current of minor strength owing to the fact that it has to pass through the resistance 37^b. For this reason 5 the contact finger 32 of the relay 23^c is not actuated and no current is sent through the relay 28^b to energize the apparatus at *d* and *e*.

10 A further effect of the current transmitted through the magnet of the relay 28^b is to cause this relay to actuate its contact finger 31, and this operates to close a stick circuit through a wire 42 and thence through the 15 contact finger 31, to the wire 39, and this stick circuit acts, as will be described later, to maintain the current in the line circuit to *c* after the relay 23^b is deenergized.

The contact finger 29 of the relay 28^b is 20 not actuated to close its circuit at this time. This contact finger is controlled by an armature which is mechanically connected with the armature which controls the contact finger 24 of the relay 23^b, and since the latter 25 armature has already been attracted by its relay magnet the contact finger 29 is thereby held in open-circuit position until it is later released by the deenergization of the relay 23^b. This preponderance of the magnet 23^b 30 may be attained by making this magnet stronger than the magnet 28, and by making its air gap shorter than that of the magnet 28 when their armatures are in their present positions, or either of these expedients may 35 be employed.

After the train has short-circuited and released the stick relay 71 by engagement with the contact member 34^b and has thereafter entered the block BC and disengaged the 40 contact member, current ceases to flow through the wire 35 to *b* and the relay 23^b is deenergized. The contact finger 24 is thereby released and the track circuit is thereby at once deenergized in the block as the train 45 enters it. At the same time the release of the contact finger 32 opens the circuit through the relay 28^b controlled thereby, but this does not affect the relay 28^b since it has already established a stick circuit, as before de- 50 scribed.

Since the train has entered the block BC, it is necessary to energize the track circuits in the block DE, as well as in the block CD which has already been energized, and this 55 is accomplished by an automatic action by which the current from *b* to *c* is raised to full strength, so that the apparatus at *c* operates to send current of minor strength to *d* and *e*. This action is consequent upon the 60 release of the contact fingers 24 and 29^b by the deenergization of the relay 23^b. The contact finger 29, immediately upon its release, is actuated to close a circuit which passes from the third rail around the resistance 37, through the wire 36 to the contact 65

finger 29, and thence through the fixed contacts of the contact fingers 29 and 31 to the contact finger 31, and thence through the magnet of the relay 28 and through the line wire 26 to *c*. Since this current is of full 70 strength it causes the relay 28^c to be fully energized so as to actuate its contact finger 32, which now closes the circuit through the resistance coil 37^c, the magnet of the relay 28^c, the line wire 26, and the relays at *d* and 75 *e*. This current is of minor strength and as the apparatus at *c* is substantially the same in arrangement as the apparatus at *b* and *e*, it acts to energize the track circuits in the western half of the block DE. 80

The eastern half of the block DE is controlled at the same time by a relay 66, of which the magnet is interposed in the line wire 26. This relay, through its contact finger 67, controls the circuit including the 85 track rails and the secondary winding 21 of the track transformer at *d*, and thus this transformer is thrown into operation and the eastern half of the block is energized simultaneously with the western half. 90

When the train reaches the end of the block BC, it operates to restore the apparatus at *b* to normal deenergized condition by short-circuiting the relay 28^b. As soon as the train leaves the contact member 34^c and 95 enters the block CD, the relay 23^c is deenergized, and the operations of the apparatus are advanced through another block in the same manner as when the relay 23^b was deenergized, as above described, and 100 thereafter the same series of operations is continued as the train proceeds through the system.

Not only are the track circuits of the block occupied by a train deenergized by 1 the action of the train upon the automatic apparatus so that short-circuiting of the track transformers is normally avoided and waste of current obviated, but the operation 1 of the apparatus is such as to prevent a 1 train in the rear of an occupied block from energizing the track circuit or circuits in that block in the usual manner. This result is secured by the mechanical connection 1 of the armatures controlling the contact fingers 24 and 29. When a block is occupied by a train the condition of the relays 23 and 28 controlling that block is such, in accordance with the series of operations hereinbefore described, that the contact fingers 24 and 29 are under the control of the relay 28, which is energized at the time, with its armature in position of closest approach, while the armature of the relay 23 is in position of greater recession. This 1 relation of the air gaps of the two magnets 23 and 28 causes the magnet 28 to preponderate, notwithstanding the magnet 23 was in preponderance when the armatures were 1 in their reverse positions. Under such cir-

5 cumstances current transmitted to the relay 23 consequent upon the advance of a train in the rear is ineffective to actuate the contact finger 24, and therefore the transformer circuit cannot be closed until the train leaves the block and deenergizes the relay 28 so as to release the contact finger 24 and permit it to be actuated by the relay 23.

6 Where a spur or siding enters a block, apparatus 10 may be provided of a character similar to that at *a* for initiating the operation of the track-circuit controlling apparatus. Such an arrangement is illustrated in Fig. 1. A siding or spur 86 enters the block 15 BC. The third rail 87 of the spur is energized from the same source as the third rail 2, as indicated by a connection 88 between the rails, and a contact member 89 is located near the switch so as to be engaged 20 by a train as it passes from the spur to the main line. The contact member 89 is connected with the magnet of a neutral relay 90 analogous in its operation and construction with the relay 71 above described, and 25 from this relay the current flows through a wire 91 to the line wire 26 and the relays at *c*. The contact finger 92 of the relay 90 operates a stick circuit as in the case of the relay 71, and is released when the train 30 which has entered the main line reaches the end of the block and engages the contact member 34^c.

35 The function of the resistance coils 33 may now be described. In the operations of the relays above described current of "full strength", that is, of strength sufficient to actuate the contact fingers 32, flows sometimes through a circuit embracing the magnet of the relay 23 alone, and at other 40 times through a circuit embracing also the magnet of the relay 28 at the block next in the rear. Since the natural line resistance is relatively slight, this change in the condition of the circuit would greatly 45 modify its resistance and cause a considerable variation in the strength of the "full-strength" current, except for the use of the additional resistance 33. This so increases the line resistance that the resistance of the 50 relay magnets is comparatively slight, so that the proportionate change in the total resistance in the circuit, due to the inclusion of a relay magnet, more or less is negligible or well within convenient limits. This 55 resistance 33 also reduces the strong currents in the third rail sufficiently to permit their use in relay magnets of low resistance.

60 The automatic track-circuit controlling apparatus hereinbefore described may be used with signal systems otherwise operating upon either of the normal danger or the normal safety principle, the effect, in the latter case, being, as before pointed out, to 65 convert the system to the normal danger principle owing to the normal deenergiza-

tion of the track circuits. The signal system chosen for purposes of illustration may now be more particularly described.

70 The signal-controlling apparatus comprises, in addition to the track relays above referred to, a line relay 43 at each station. This relay is of the same type as the track relays, having an armature 44 provided with a coil and a contact finger 45. It has in addition, however, a neutral armature and 75 contact finger 46, which is operated whenever the field is energized, and in the line relay it is the armature coil which is constantly energized by connection with the wires 9 and 11 and the transformer 12, 80 while the field magnet is connected with the line circuit and controls the operation of the relay.

85 The home signal 47 is controlled by the neutral contact finger 46, and the distant signal 48 by the polarized contact finger 45. Both signals have a bias to danger position, but are provided with electric apparatus of any ordinary or suitable form for moving them to clear position. When the contact finger 46 is raised, current passes from the wire 9 through a wire 51 to the signal 47, thence to the fixed contact coöperating with the contact finger 46, and from the latter by a wire 49 to the wire 11. A circuit-breaker 53 is mechanically connected with the home signal so that when the latter is 90 clear the circuit-breaker engages a coöperating fixed contact. Under these conditions the distant signal 48 may also be cleared, by 100 the operation of the polarized contact finger 45, the current passing from the wire 9 through the wire 51, the circuit-breaker 53, wire 52, the distant signal 48, the wire 54, the contact finger 45 and the wire 49 to the wire 11. The circuit-breaker 53 does not affect in any way the normal operation of the apparatus, since the distant signal is never cleared alone, but this circuit-breaker 105 is merely a precautionary device to prevent 110 the clearing of the distant signal in case the home signal, through mechanical causes, fails to clear when its electric operating device is energized.

115 The selective operation of the signals, by which either the home signal alone or both the home signal and the distant signal are cleared, is effected by reversal of polarity in the line circuit, with the consequent action 120 of the line relay. To effect such reversal, two contact fingers 55 and 56 are mechanically controlled by the home signal 47 (except at station B), being raised and lowered therewith. These contact fingers constitute 125 a pole-changing switch, and operate in a manner to be presently described.

130 In a short block such as the block CD, a set of apparatus, such as that at C or D, constitutes the entire signal-controlling apparatus at each end of the block, but in a

long block like DE, which is divided in the middle, additional line relays 78 and 79 are interposed in the line circuit, the line wire 61 being connected with fixed contacts 5 controlled by the contact fingers 81 and 82 of these relays, while the contact fingers are connected by a wire 83. The relays 78 and 79 are similar in construction and operation to the track relays 7 and 8, and their fields 10 are energized by a transformer 80 fed by the transmission line. The armature coils of these relays are connected with inductive track coils 76 and 77 similar in operation to the track coils 5 and 6. The relays 78 and 15 79 are thus energized by the track circuits, but they operate, in the same manner as the regular track relays, to open the line circuit when their track coils are deenergized by the presence of a train near the middle 20 of the block.

The normal condition of the signal-controlling apparatus is shown in Fig. 1, the signals being at danger, the line circuits and the track circuits deenergized, and all the 25 relay-controlled contact fingers being in open-circuit position. Suppose, now, that a train occupies block BC and approaches C. The track circuits in CD and DE are now energized by the automatic apparatus, as above 30 described, and track coils 5^c, 5 and 6^d, 76, 77 and 6^e are energized, causing the corresponding track relays to actuate their contact fingers in case both blocks are clear. The home signal at D is now cleared as follows: 35 Current flows from the wire 9^e, through the wire 51^e, the contact finger 55, and the wire 57 to the line wire 58, and thence to station D. From the line wire the current passes through the wire 59 to the contact 40 finger, now in closed-circuit position, of track relay 7^d, and thence through the field magnet of the line relay 43^d. The current returns through the line wire 61 to the contact finger 18 of the track relay 8^e, which is 45 now in closed-circuit position, and thence by the wire 62 and the contact finger 56 to the wire 11.

The line relay 43^d being energized, as 50 above described, the neutral contact finger 46 is raised and the home signal is cleared. The current is of such polarity, owing to the 55 position of the pole-changing switch at E, that the polarized contact finger 45^d is not raised, and distant signal 48^d is not cleared. A somewhat similar operation occurs in 60 block CD. Here, however, owing to the reversal of the position of the pole-changing switch at D, resulting from the clearing of the home signal there, the current in the line wire is of such polarity that both contact fingers of the line relay 43 are actuated, and thus both signals are cleared at C. As soon 65 as the train enters the block CD, the track circuits of that block are automatically deenergized, as before described, and the sig-

nals at C return to danger. At the same time the track circuit of block EF is energized, the home signal at E is cleared, the current in the line wires connecting D and E is thereby reversed in polarity, and the distant signal at D is cleared in addition to the home signal. These operations are repeated throughout the line as far as it is clear. Suppose, however, a second train approaches C while the first train is in block 75 CD. The track circuit in CD is not energized through the action of the automatic apparatus for the reason heretofore given, but even in case it should be energized through some accidental action, such as the sticking 80 of a relay, the signals at C still can not clear. Owing to the presence of the first train, one or the other branch of this track circuit is short-circuited, and one of the track coils 5^c or 6^d is deenergized. One of the line relays 7^c or 8^d is thus deenergized, and the line circuit is interrupted. No current can flow from D to C and both signals at C remain at danger. As soon as the first train passes from block CD into block DE, the 90 line circuit CD is restored, and as the home signal 47^d remains at danger, the current transmitted is of such polarity that the home signal alone at C is cleared, thus admitting the second train to CD with a cautionary distant signal. 95

In the absence of the automatic controlling apparatus for the track circuits, the above-described signal system operates as a normal safety system, for all the track circuits, track relays, line circuits and line relays are normally energized and the signals are maintained clear by their electric operating devices. 100

The present invention is applicable to any signal system or to a traffic-controlling system of any kind in which track circuits are employed, and it may be arranged to control any required number of blocks in advance of a train. 110

It is obvious that various modifications may be made in the embodiment of the invention hereinbefore described and illustrated in the accompanying drawings within the nature and scope of the invention as defined in the following claims. 115

Where the term "train" is used in the claims it is to be understood as covering any rolling stock, whether a single car or locomotive or several members coupled together. 120

I claim:

1. A traffic-controlling system comprising track circuits, means for energizing them, and means acting automatically to deenergize the track circuit in the portion of the line occupied by a train. 125

2. A traffic-controlling system comprising normally-deenergized track circuits, and means acting automatically to energize the track circuits successively ahead of a train 130

moving through the line and to deenergize the track circuit at the point occupied by the train.

- 5 3. A traffic-controlling system divided into blocks, track circuits each occupying substantially the whole of a block, and means acting automatically to energize a block ahead of a train and to deenergize the block occupied by the train.
- 10 4. A traffic-controlling system comprising track circuits, and relays for controlling the track circuits each having two contact fingers responsive to currents of different characters, one contact finger controlling one track circuit and the other contact finger controlling an adjacent track circuit.
- 15 5. A traffic-controlling system comprising a track having continuously-conductive rails and cross-bonds constituting track circuits,

traffic-controlling devices responsive to currents in the track circuit, and means, normally inactive, for energizing the track circuits, said means operating automatically, under control of a train to energize a track circuit in advance of the train without energizing the track circuit occupied by the train. 20 25

6. A traffic-controlling system comprising traffic-controlling means, a traffic-controlling rail circuit in control thereof, and means for deenergizing the rail circuit when a train is present thereon. 30

In testimony whereof I affix my signature in presence of two witnesses.

ALBERT V. T. DAY.
